TRAY FOR BEVERAGE INGREDIENT DISPENSING MACHINE

Thomas F. Hines, Arcadia, Calif., assignor to Brucof
Company, Arcadia, Calif., a co-partnership

Filed Feb. 5, 1962, Ser. No. 68,691

Term of patent 14 years

(Cl. D44—10)

I claim:

The ornamental design for a tray for beverage ingredient dispensing machine, as shown.
